UNITED STATES PATENT OFFICE

ROBERT S. McELHANEY, OF SHADYSIDE, OHIO

GAP INDICATING MECHANISM FOR RAILWAY SWITCH SIGNALS

Application filed June 24, 1931. Serial No. 546,461.

This invention relates broadly to railway switch signals, and it has for its primary object to provide a signal whereby may be indicated visually to the engineman of an approaching locomotive and to others whether or not the therewith associated switch point occupies fully closed relation to the main track rails.

A further object is to provide, in association with a signal of the character mentioned, automatic control mechanism adapted alike to actuate said signal to its warning, or danger-indicating, position whether the shiftable switch point occupies its fully open or a partially open position.

A still further object is to provide a signal of the character mentioned associated with manually operated mechanism for effecting throwing of the switch to and from open position, and adapted for visually indicating the presence of gaps between the switch points and the track rails, as when such points are not fully seated, such mechanism being operable without disturbance of the automatic control mechanism.

With these and other objects in view, the invention resides in the features of construction, arrangement of parts, and combinations of elements which will hereinafter be described, reference being had to the accompanying drawings, in which—

Figure 1 is a plan view of a railway switch equipped with my invention;

Figure 2 is an enlarged section on line 2—2, Fig. 1;

Figure 3 is an enlarged top plan view of the casing for the trigger-release and the therewith associated parts, the cover for said casing being removed;

Figure 4 is a section on line 4—4, Fig. 3;

Figure 5 is a section on line 5—5, Fig. 4;

Figure 6 is an enlarged section on line 6—6, Fig. 2;

Figure 7 is a section on line 7—7, Fig. 6;

Figures 8, 9, 10 and 11 are sections taken on line 8—8, Fig. 2, showing various positions of the rotary cam relative to the roller of the automatic signal operating mechanism; and

Figure 12 is an under side elevation of the

crank and bridle by means of which the switch points are shifted.

Referring to said drawings, 1 and 2 designate switch points which are laterally shiftable relative to stationary track rails 3 and 4, respectively, said switch points being maintained in relatively spaced relation by means of a transverse bridle 5 upon which both are rigidly mounted. Said bridle has pivotally connected to an end thereof a toggle link or arm 6 which has its opposite end pivoted upon the wrist pin 7 of a crank 8 fixed on the lower end of an upright rotary signal standard 9. While said crank 8 is herein shown as having disk form, such may manifestly be provided in various other forms, as desired.

The standard 9 has its lower end portion journaled in the base portion 10^a of a casing which is designated generally by the reference character 10 and which is rigidly mounted laterally of the trackway, as upon the extended ends of crossties 11. Said standard projects upwardly through the top of said casing 10 and has seated upon its upper end a signal lamp 12 of an ordinary type designed to be rotated throughout a 90° arc for displaying differently colored signal lights indicating, respectively, open and closed positions of the switch.

A tubular member 13 loosely embraces the upper end portion of said standard and has said lamp removably seated thereon. The lower end of said member, which is provided with opposite longitudinally extending open slots 14, is received within a neck portion 10^b formed on the top of said casing 10 and has therein a counterbore 15 of enlarged diameter in which is loosely received the upper end of a sleeve 16 which is adapted for both vertical and rotary shifting movements on said standard, as will hereinafter be explained.

Fixed upon the standard 9 within the lower part of the casing 10 is a bevel gear 17 which has operatively engaged therewith a bevel gear 18 carried on the inner end of a 95 suitably journaled horizontal shaft 19 which projects outwardly through said casing and carries upon its outer end a shift lever 20 of the usual weighted type employed for manually throwing the switch points of rail-

way switches. Said lever is shiftable, as ordinarily throughout 180° to and from the switch-closing position shown in Fig. 1, being received at the opposite limits of its movement by suitable supports, as 21 and 22. The gears 17 and 18 are so proportioned relatively that in each approximate half revolution of the gear 18, actuated by shifting of the lever 20 from either of its limits of movement to the other, the gear 17 is rotated throughout approximately a quarter revolution for turning the standard 9 and the superposed lamp 12 throughout a corresponding part of a revolution. Obviously, such movement simultaneously effects, through the intermediacy of the crank 8 and the thereto-connected bridle 5, the shifting of the switch points 1 and 2 from one limit of movement to the other.

Received within the open slots 14 of the tubular member 13, hereinbefore referred to, are oppositely disposed pins 23 fixed in the upper end portion of the sleeve 16. Said sleeve has therein opposite diagonally extending, or spirally inclined, slots 24 in which are received oppositely disposed pins 25 fixed in the standard 9, as shown in Figs. 2 and 6. In the closed position of the shiftable switch points, said sleeve 16 occupies its elevated position wherein the pins 23 are disposed at the upper ends of said slots 14 and the pins 25 are disposed at the lower ends of the slots 24.

Formed on the lower end of said sleeve 16 is an annular collar or flange 26 which occupies loosely embraced position within a central circular socket 27 provided therefor in a head 28 formed on the upper end of a second sleeve 29 within which the standard 9 is relatively rotatable. A cap 28^a rigidly mounted upon said head 28 in overlying relation to said flange 26 serves to retain said sleeve 16 and 29 against relative longitudinally movement while permitting independent rotary movement of the sleeve 16. Oppositely disposed pins or trunnions 30 fixed in said sleeve 29 have pivoted thereon the opposite members of a sleeve-encircling yoke 31 formed intermediate the ends of the approximately horizontal arm 32^a of a bell-crank lever 32. Said arm 32^a crosses the interior of the casing 10 and has that end thereof adjacent to its related arm 32^b projecting outwardly through an opening 33 provided therefor in the wall 55 of said casing. Said lever is pivotally mounted at or adjacent to the angle between its said arms 32^a and 32^b upon a support, as the casing-carried bracket 34. The arm 32^b occupies a pendent position and has its lower end pivotally attached to an end of a connecting rod 35 which thence extends horizontally toward the trackway with its opposite end projecting into the interior of a box-like housing 36 through an aperture 37 provided in the outer wall of the latter.

The housing 36 is suitably mounted, as upon said cross-ties 11, adjacent to the outer side of the track rail 3. Suitably journaled within said housing is a horizontal shaft 38 which substantially parallels said track rail 70 and which has formed therein or thereon a crank 39, herein shown as of U-form, to which is attached the adjacent end of the connecting rod 35 and which, in the closed position of the switch point 1, occupies upstanding position, as shown in Figs. 2, 3 and 4. Rigidly carried by said shaft and disposed normally in a horizontal position is an arm 40, herein shown as of flat plate-like form, wherein its free end overlies and is supported by the adjacent extreme edge portion of a projecting ledge or lip 41 formed on a head-like member 42 which is rigidly carried upon the upper end of an upright post 43. Said post, which is rigidly carried by, or forms an integral part of, a horizontal arm 44 that extends transversely beneath the track rail 3, is shiftable with movements of said arm 44, as will presently be explained, such shifting being permitted by the provision of a suitable opening or slot 45 in the bottom of said housing 36.

The arm 44 is carried in fixed relation to the pointed end of the switch point 1, being preferably formed as an integral part of a bar or plate 46 which is bolted upon and projects forwardly from said pointed end of said switch point, as shown. A pin 47 directed horizontally through the head 42 of the post 43 has its opposite ends horizontally 100 shiftable in channels 48 provided therefor in transverse walls of the housing 36, as shown in Figs. 3, 4 and 5.

In the normal position of the parts, wherein the switch point 1 occupies seated relation to the track rail 3, the bell-crank 32 is disposed with its arm 32^a in substantially the full line position shown in Fig. 2, the outer end thereof being elevated to the extent that a roller 49 carried thereby is wholly removed from engagement with, and occupies the elevated position shown in Fig. 8, relative to a cam 50 which is fixed upon the shaft 19 of the switch-throwing mechanism hereinbefore described. Said position of the bell crank 115 is maintained through the intermediacy of the crank-shaft 38 and the connecting rod 35, the arm 40 of said crankshaft being supported against movement from its horizontal position by the underlying edge portion of the lip 41 of the head 42 of the post 43. With the bell crank occupying its said normal position, the relatively connected sleeves 16 and 29 are thereby supported in their elevated positions on the standard 9 wherein the lamp 12 is disposed in safety-indicating position, as are also the cross-arms 51 carried by the tubular member 13.

When the shift lever 20 is manually swung from its support 21 to the opposite support 131

22 for effecting opening of the switch in the manner hereinbefore described, the lamp 12 and tubular member 13 are actuated to rotate throughout a quarter revolution to display danger, or caution, signals. Such rotation is effected, first, through the rotary movement imparted through the gear 17 to the standard 9; thence to the sleeve 16 through the standard-carried pins 25 engaged therewith at the lower ends of the slots 24 thereof; thence to the tubular member 13 through the sleeve-carried pins 23 engaged therewith at the upper ends of the open slots 14 thereof.

15 Return shifting of said shift lever reverses the movements just described, returning the tubular member 13 and the thereby carried lamp 12 to safety indicating positions.

At the beginning of the above described switch-opening movement of the parts effected by manual throwing of the shift lever 20, a nose 50^a formed at the highest part of the cam 50 and off which the roller 49 borne by the bell crank arm 32^a rides just prior to seating of said lever with respect to its support 21, promptly engages the adjacent under side of said roller and thrusts the latter to a slightly elevated position as it moves into underlying relation thereto. This slight elevating movement acts through the bell crank 32, the connecting rod 35, and the crank-shaft 38 slightly to elevate the arm 40 from its seated position for permitting the latter freely to shift away from underlying relation to said arm in the manually actuated switch throwing operation. Due to the fact that the outer peripheral surface 52 upon which said roller rides from an end of the shifting movement to the other is in the arc of a circle having its center at the axis of the shaft 19 by which said cam is carried, said elevated position of said arm 40 is maintained until said lip is unobstructedly returned into underlying relation thereto. As the cam rides from beneath said roller at the end of the switch closing movement, the arm 40 is permitted to drop to the position wherein it is again supported by said lip 41.

Should the switch point 1 fail to fully close, as by reason of an unnoticed obstruction preventing seating of said point against the rail 3, the lip 41 will thereby be prevented from assuming underlying relation to the arm 40 of the crankshaft 38. Thus, when the cam rides from beneath the roller 49, the impulse resultant upon the drop of the outer end of the bell crank 32 and the therewith associated movable parts, together with the weight of said parts, will carry the latter unobstructedly to the dotted line positions indicated in Figs. 2, 5 and 8. With such downward movement of the arms 32^a of the bell crank, the connected sleeves 16 and 29 are permitted to gravitate to lowered positions on the standard 9, the sleeve 16 being actuated in its downward movement, where-

in the inclined slots 24 thereof cooperate with the pins 25 of said standard to rotate throughout a quarter revolution for actuating corresponding rotation of the therewith interengaged tubular member 13 carrying the lamp 12, thus positioning said lamp and the signal arms to display the warning signal. 70

In the event that, following closing of the switch, the switch point 1 should unauthor- 75 izedly or unintentionally be shifted, either wholly or throughout the slight distance which might create a hazard, the lip 41 is thereby withdrawn from supporting relation to the arm 40 of the crankshaft, whereupon the hereinbefore described parts constituting the automatic signal operating mechanism will be permitted to gravitate in the manner last above described for actuating the lamp and the signal arms to assume 80 warning positions.

At the beginning of the above described switch-opening movement of the parts effected by manual throwing of the shift lever 20, a nose 50^a formed at the highest part of the cam 50 and off which the roller 49 borne by the bell crank arm 32^a rides just prior to seating of said lever with respect to its support 21, promptly engages the adjacent under side of said roller and thrusts the latter to a slightly elevated position as it moves into underlying relation thereto. This slight elevating movement acts through the bell crank 32, the connecting rod 35, and the crank-shaft 38 slightly to elevate the arm 40 from its seated position for permitting the latter freely to shift away from underlying relation to said arm in the manually actuated switch throwing operation. Due to the fact that the outer peripheral surface 52 upon which said roller rides from an end of the shifting movement to the other is in the arc of a circle having its center at the axis of the shaft 19 by which said cam is carried, said elevated position of said arm 40 is maintained until said lip is unobstructedly returned into underlying relation thereto. As the cam rides from beneath said roller at the end of the switch closing movement, the arm 40 is permitted to drop to the position wherein it is again supported by said lip 41. 90

The cam 50 is designed to provide means whereby the parts of the automatic signal operating mechanism described may be restored to their normal positions following 95 operation thereof, as when the obstruction preventing closing of the switch has been removed, by the mere act of throwing the shift lever 20 to switch opening position and returning it to switch closing position. A ledge 53 is provided on the cam and receives thereon the roller 49 at the limit of the downward drop of the latter when the automatic signal operating mechanism is called into play, as described. Said ledge is coincident 100 with a second cam surface 54 whereon said roller may travel to the outer peripheral surface 52 whereon said roller has normal travel, meeting said surface 52 at a point adjacent to the limit of the switch-closing rotation of said cam. Said cam surface 54 is formed, first, by the provision in the inner face of said cam of a curved groove or channel 55 beneath the nose 50^a, and, second, by the formation in said inner face of a recess 56 which extends outwardly through the peripheral cam surface 52, as shown. A tongue 57 is pivotally mounted upon the cam within the front end of said recess 56 and normally occupies the position shown in 105 Figs. 8, 10 and 11 wherein its outer surface complements and coincides with said peripheral cam surface 52, being yieldingly retained in said position, as by a thin leaf spring 58 which has an end rigidly attached 110 to said cam adjacent to the nose thereof and which has its other end portion disposed in overlying seated relation to said tongue.

As the cam is rotated toward switch-opening position, the roller 49 enters the channel 55 and travels upon the cam surface 54 until it rises to the peripheral surface 52 at the approximate point of rest shown in Fig. 10. In its said travel the point of the tongue 57 is elevated thereby and rides thereon, as in 115 120 125 130

dicated in Fig. 9. In the normal forward and reverse travel of the cam, said roller rides over said tongue, as shown in Fig. 11, the outer surface of the tongue being coincident 5 with the peripheral cam surface 52.

What is claimed is—

1. A gap indicating signal for railway switch points including a rotatable standard, means connecting the switch point and standard, means for actuating the switch point and standard in unison, a rotatable and vertically movable signal on said standard, means carried by the actuating means for moving the signal to its elevated position, 15 latch means for retaining the signal in its elevated position, and means carried by the switch point for releasing the latch and thereby the signal to permit the latter to move to its signalling position upon unauthorized movement of the switch point.

2. A combination of a railway switch and means for manually opening and closing said switch, said means including a rotatable shaft, of a standard adapted for 25 rotary movements with switch actuating movements of said manual means, a signal carried by said standard and adapted for rotary shifting movements independent of the latter, mechanism interposed between said 30 switch and signal whereby the latter is automatically rotated to warning position independently of the movement of said standard when the switch assumes a partially open position, and a cam carried by said shaft for 35 restoring said signal to its normal inoperative position when the switch is moved to its closed position upon operation of said manual means.

3. A gap indicating signal for railway 40 switch points including a rotatable standard, means connecting the switch point and standard, means for actuating said switch point and standard in unison, a signal carried by said standard, said signal having a 45 rotative movement independent of said standard when the switch assumes a partially opened position, means carried by the actuating means for moving the signal to its non-signalling position independent of the standard, and means for releasing the signal 50 whereby to permit the latter to move to its signalling position independent of said standard upon unauthorized movement of the switch point.

55 4. A gap indicating signal for railway switch points including a support, a rotatable standard mounted on said support, means connecting the switch point and standard, means for actuating the switch 60 point and standard in unison, a vertically movable signal carried by said standard having a movement independent of said standard upon unauthorized movement of the switch point, a lever pivoted intermediate 65 its ends to said support and having a por-

tion thereof engaging said signal, a cam member carried by the actuating means for engaging one end of the lever for elevating the signal to its inoperative position, latch means engaging the opposite end of said lever for retaining the signal in its inoperative position, and means carried by the switch point for releasing said latch means and thereby permitting the signal to move to its operative position upon unauthorized movement of the switch point.

In testimony whereof, I affix my signature.

ROBERT S. McELHANEY.
